PEN WITH INK CARTRIDGE EXTENSION AND RETRACTION MECHANISM

Hartley M. Sears, Laguna Beach, Calif., assignor to The Hartley Co., Costa Mesa, Calif., a corporation of California

Filed Aug. 6, 1965, Ser. No. 477,741
16 Claims. (Cl. 120—42.13)

This invention pertains to a pen, including a mechanism for extending and retracting a ball pen cartridge.

The arrangement of this invention is adaptable to the manufacture of pens having a single extensible ink cartridge, or to those that include two cartridges that are selectively operable. In the latter instance, it is possible to utilize inks of different colors, or the same ink may be in both to provide a spare ink cartridge to allow continued writing even after one cartridge is exhausted.

Previous devices for multiple-cartridge pens resulted either in an abnormally small ink supply in each cartridge or necessitated a pen with an exceedingly large diameter barrel, unattractive and awkward to hold. The present invention, however, permits a pen to be constructed with a duality of cartridges in which the barrel is of normal size, yet a full supply of ink is retained in each cartridge. Also in previous pens incorporating more than one cartridge, the arrangement for extending and retracting the cartridges has been somewhat crude and inconvenient to operate. According to this invention, however, a true push-button actuation is obtained in which a single button at the end of the pen will both extend and retract either of the cartridges. Over and above this, the invention provides a mechanism of complete reliability, which will operate with satisfaction through a long period of service. In addition, it is of low cost construction, adapted for mass production, which is always of utmost importance in the highly competitive market in which ball point pens are distributed.

An object of this invention is to provide an improved extension and retraction mechanism for a pen cartridge.

Another object of this invention is to provide an arrangement adapted for the selective extension and retraction of a duality of ink cartridges in a ball point pen.

An additional object of this invention is to provide a ball pen extension and retraction mechanism adaptable for a pen of single-cartridge construction, or for a pen having more than one cartridge.

Another object of this invention is to provide a ball pen extending and retracting mechanism that is push-button operated and is of low cost, yet reliable, construction.

A further object of this invention is to provide a ball pen capable of incorporating a duality of ink cartridges, and including an extending and retracting mechanism of compact nature, permitting the pen to be attractively styled and of a size best adapted for being held in the hand for writing, while at the same time providing a large ink supply in each cartridge.

An additional object of this invention is to provide a multiple-cartridge ball pen allowing the selective extension of the cartridges through the use of only a single push button.

Yet another object of this invention is to provide a multiple-cartridge ball point pen which is readily indexed for selecting the desired cartridge for extension for writing.

A still further object of this invention is to provide an ink cartridge extension and retracting mechanism which is push-button operated, yet allows virtually the entire length of the pen to be occupied by the cartridge so that a maximum ink supply is obtained.

2

These and other objects will become apparent from the following detailed description taken in connection with the accompanying drawing in which:

FIGURE 1 is a perspective view, partially broken away, of a pen incorporating this invention;

FIGURE 2 is an enlarged fragmentary sectional view of the upper portion of the pen of FIGURE 1 with the cartridge in the retracted position;

FIGURE 3 is a view similar to FIGURE 2 with the cartridge extended;

FIGURES 4, 5 and 6 are transverse sectional views of the pen taken along lines 4—4, 5—5 and 6—6, respectively, of FIGURE 1;

FIGURE 7 is a perspective view of one of the ink cartridge assemblies;

FIGURE 8 is a perspective view of the upper end member of the ink cartridge separated from the remainder of the cartridge;

FIGURE 10 is a fragmentary perspective view of the central portion of the pen, including the rotatable collar;

FIGURE 11 is an enlarged perspective view, partially broken away, of the upper sleeve insert that is received in the cap;

FIGURE 12 is a fragmentary view of the actuating arm engaging the upper end of the ink cartridge in extending the cartridge, including a vector diagram to illustrate the forces imposed on the cartridge;

FIGURE 13 is a view similar to FIGURE 12 but with the actuating arm engaging the cartridge to retract it;

FIGURE 14 is a fragmentary sectional view of a modified construction in which a pivotal element is included at the upper end of the cartridge and the cartridge does not tilt during extension and retraction;

FIGURE 15 is a fragmentary sectional view of an embodiment in which the pivotal member at the upper end of the cartridge has a hinged connection.

FIGURE 16 is a fragmentary sectional view of a further modification in which deflectable tabs are included on the cartridge carrier for locking the cartridges in the extended position;

FIGURE 17 is a fragmentary perspective view of the portion of the carrier of FIGURE 16 that includes the tabs;

FIGURE 18 is a fragmentary sectional view of the invention as utilized for a single-cartridge pen;

FIGURE 19 is an exploded view of the parts that fit within the cap of the arrangement of FIGURE 18; and

FIGURE 20 is a sectional view of a modification in which the actuating arm is integral with the push button.

With reference to the drawing, the arrangement of this invention as shown in FIGURES 1, 2, and 3 is applied to a pen 20 of dual-cartridge construction providing for the selective extension or retraction of either of two ink cartridges. The tubular housing of the pen includes a barrel 21, above which is a rotatable collar 22 that is utilized in selecting the cartridge desired. Beyond the collar 22 is the cap 23 having a tapered frustoconical end 24 out of which projects a push button 25. The latter element is used in extending or retracting either of the cartridges contained within the pen.

Extending for a substantial portion of the length of the pen is a carrier 27 for the ink cartridges 28 and 29. Typically, the cartridges 28 and 29 will contain inks of different colors, such as red and blue, permitting the pen to write in different colors through the selection of these cartridges. In other respects, the cartridges 28 and 29 are identical. Thus, the cartridge 28 has a bottom cylindrical portion 30 at the tip of which is a rotatable ball 31 of conventional construction, which dispenses the ink from the cartridge to the writing surface. Above the

relatively short cylindrical portion 30 is the main reservoir 32 of the cartridge 28, which is of oval cross section, as best seen in FIGURES 4 and 5. An element 33, which normally is made of plastic, has a lower section 34 that fits into the upper end of the reservoir portion 32 of the cartridge 28, where it is retained by friction force. The remainder of the end member 33 projects beyond the reservoir to cooperate with the indexing and extending mechanism in the use of the pen of this invention.

The corresponding components of the other cartridge 29 include the short cylindrical section 35 having a ball tip 36, connecting also to an oval reservoir section 37, beyond which is the member 38 that cooperates with the actuating mechanism within the pen.

At its bottom end, the carrier 27 includes a disc 40 of circular periphery, generally complementary to the inner wall of the barrel 21, which also is of circular configuration. The disc 40 on one side of the axis includes an opening 41, through which extends the cylindrical portion 30 of the cartridge 28. Similarly, on the opposite side of the axis is a circular opening 42 that receives the cylindrical portion 35 of the other cartridge 29. Inwardly of the disc 40 the carrier 27 is in the form of a continuous elongated web having opposite arcuate surfaces 43 and 44 which receive the oval reservoir portions 32 and 37 of the cartridges 28 and 29. Thus, the surfaces 43 and 44 are substantially complementary to one side of each of the sections 32 and 37 of the ink cartridges. The edges 45 and 46 that interconnect the surfaces 43 and 44 are defined by cylindrical segments having the same radius of curvature as that of the disc end 40, hence being substantially complementary to the inner wall of the barrel.

Near the end opposite from the disc portion 40, the surfaces 43 and 44 terminate, extending into flat parallel surfaces 47 and 48. A rectangular opening 49 extends through the wall of the carrier and so communicates with both the surfaces 47 and 48.

Inwardly of the flat surface portions, the radius defining the outer edges of the carrier 27 is reduced so that there are provided surfaces 52 and 53 having a diameter smaller than that of the surfaces 45 and 46. These cylindrical edges terminate short of the end of the carrier 27 so that the outer section is rectangular in cross section, having flat parallel side edges 54 and 55.

Adjacent the end disc portion 40, the surfaces 43 and 44 of the carrier 27 are provided with shallow elongated recesses 57 and 58. These receive the inner sides of light wire compression springs 59 and 60 which circumscribe the cylindrical portions 30 and 35 of the ink cartridges 28 and 29. One end of each spring bears against the disc portion 40, while the opposite ends engage the outwardly flared parts where the cartridges change from cylindrical to oval cross section. Hence, the springs 59 and 60 can bias the cartridges inwardly with respect to the barrel 21. The springs are captured between the inner wall of the barrel and the confines of the recesses 57 and 58 so that they are retained in place even upon removal of the cartridges 28 and 29.

As shown in FIGURE 1, a split sleeve 62 circumscribes the upper portion of the carrier 27 and the ink cartridge it contains. The sleeve 62 normally is of metal, having a longitudinally split lower portion 63 press-fitted into the upper end of the barrel 21. The section 63 of the sleeve fits around the arcuate edges 52 and 53 of the carrier 27, abutting the shoulders formed where the sides of the carrier become larger at the edges 45 and 46. Beyond the lower section 63, the sleeve 62 extends through the collar 22 and into the cap 23. In the area of the collar 22, the sleeve 62 includes a circumferential slot 64 extending slightly more than 180°. Above this is a longitudinally extending slot 65 that reaches to the opposite end 66 of the sleeve. The end 66 inclines outwardly away from the slot 65 and may be defined by a helical curve. Alternatively, the end 66 may be a straight sur-

face at an angle such as 45° with respect to the axis of the sleeve 62, or of some other outwardly inclined configuration.

A small tab 67 is bent outwardly from the circumference of the sleeve 62 and fits within a slot 68 at the inner end of the cap 23 (see FIGURE 2). Therefore, the sleeve 62 prevents the cap from rotating with respect to the barrel 21. Also, this rotationally locates the cap with respect to the sleeve 62 so that these parts always are assembled in the same alignment.

Above the sleeve 62 in the cap 23 is a member 69 having a lower cylindrical portion 70 press-fitted into the cap. The bottom edge 71 of the lower portion 70 of the element 69 is of the same curvature and spaced slightly away from the end wall 66 of the sleeve 62. Therefore, the edges 66 and 71 cooperate to define an oblique annular groove 72, which at its lower part communicates with the vertically extending slot 65 of the sleeve 62. Immediately above the slot 65, the edge 71 is provided with a slight indentation 73.

The annular groove 72 defined by the edges 66 and 71 is utilized in indexing the ink cartridges 28 and 29 for selective extension and retraction by the mechanism to be described below. In connection with the indexing of the cartridges, the upper end elements 33 and 38 of the cartridges 28 and 29 are provided with outwardly extending tabs 75 and 76 that are received in the groove 72. As a result of this, the cartridge 28, being at the left-hand side of the pen as illustrated in FIGURES 2 and 3, is held at the lowermost portion of the groove 72 because of the presence of the tab 75 in the groove. In this position, the lower cylindrical portion 30 with the ball point 31 is projected into the tip section 77 of the barrel 21. This part of the barrel is not symmetrical, but is offset so that its opening 78 is radially on the same side of the pen as the slot 65 in the sleeve 62. Hence, when the cartridge 28 is positioned as illustrated in FIGURES 2 and 3, where the cartridge is pushed downwardly by the reaction of the tab 75 on the wall of the groove 72, the cylindrical portion 30 of the cartridge 28 is aligned with the opening 78 in the tip 77 of the barrel. The indentation 73 in the edge 71 of the member 69 acts as a detent as the cartridge 28 is biased upwardly against it by the spring 59, rotationally locating the cartridge 28 directly opposite from the opening 78 in the tip 77 of the barrel.

While the cartridge 28 is held downwardly by the tab 75 in the groove 72, at the same time the cartridge 29 is maintained in a raised position. This comes about from the tab 76 in the groove 72, with the groove thereby holding the cartridge 29 elevated with respect to the barrel. This retracts the cylindrical portion 35 of the cartridge 29 from the tip 77 of the barrel. Here, the cartridge 29 is held in a position where it is beyond the influence of compression spring 60, so that it is subjected only to gravitational forces when it is in the raised position of FIGURES 2 and 3. The springs 59 and 60 are devised to exert an upward force on either cartridge only to a point where the cartridge is lightly above the lower section of the groove 72. Therefore, beyond this point, the springs 59 and 60 do not cause a frictional drag force to be generated between the tabs 75 and 76 and the upper edge 71 of the groove 72.

The cartridges 28 and 29 may be selectively positioned in alignment with the opening 78 of the tip so that each may be indexed for subsequent extension to the writing position. This movement comes about through rotation of the collar 22. A recess 80 is provided in the lower edge of the collar 22, and this receives a tab 81 that extends outwardly from the edge portion 52 of the carrier 27. The tab 81 also passes through the slot 64 in the sleeve 62. Consequently, when the collar 22 is rotated, the tab 81 and hence the carrier 27 are caused to turn with it. The slot 64 is dimensioned so that the collar may be rotated through an arc of 180°. Hence, the carrier 27 is turned through a similar arc about its longitudinal axis.

When this occurs, the tabs 75 and 76 cooperate with the confines of the guided passageway formed by the groove 72 to reposition the cartridges 28 and 29. In other words, if the collar 22 is rotated clockwise 180° as the device is viewed from the top in the sectional illustrations of FIGURES 4, 5 and 6, the tab 76 will ride downwardly in the groove 72, forcing the cartridge 29 to a lower position while the carrier turns the cartridge 29 through an arc of 180°. At the same time, the cartridge 28 also moves through an arc of 180° and axially is lifted up by the tab 75 and the groove 72. This reverses the positions of the cartridges 28 and 29.

As noted above, the lowermost of the cartridges, i.e., the one aligned with the opening 78 in the tip 77, is in position for ejection to the writing position. The arrangement for extending the cartridge includes an actuating member 83, best seen in FIGURES 1, 2 and 3. A flat disc portion 84 is at the upper end of the actuating member, and a depending arm 85 extends from one edge of the disc section 84. The portion 84 of the actuating member 83 includes a central aperture that receives a short post 86 depending from the push button 25. The section 86 of the push button, in turn, is provided with an axial opening 87 that slidably receives an upstanding post 88 located at the axis of the pen and projecting from the radial wall 89 of the member 69. A compression spring 90 circumscribes the post 88 and the cylindrical part 86 of the push button, one end of the spring bearing against the wall 89 of the member 69 and the opposite end engaging the undersurface of the disc section 84 of the actuating member 83. The spring 90, therefore, exerts a force on the section 84 of the actuating member 83, biasing this member upwardly, which urges the push button 25 to an elevated position. The upward movement of the push button is limited by the interengagement of the lower frustoconical portion 91 of the push button and the inwardly tapering end part 24 of the cap 23.

A portion of the member 69 is cut away to provide a slot 92 in the top wall 69 connecting to a slot 93 in the cylindrical section 70 of the member 69. The latter slot extends longitudinally of the pen and is aligned with the vertical slot 65 of the sleeve 62. The actuating arm 85 of the member 83 extends through the slots 92 and 93.

The arm 85 of the actuating member 83 includes a first portion 95 extending from the periphery of the end disc section 84 at an angle of slightly under 90°. The arm portion 95 connects to an intermediate section 96 that is at an obtuse angle with respect to the first portion, and which joins with a third segment 97. The intermediate section 96 is inclined inwardly from the upper portion 95 toward the axis of the pen, while the bottom part 97 has a slight outward direction when the mechanism is in the retracted position of FIGURE 2. This locates the lower end of the section 96 at the inner edge 98 of the slot 92 in the wall 89 when the mechanism is in the retracted position. The lower portion 97 of the actuating arm terminates in an outwardly bent doubled-over end 99 which lies against the inner periphery of the cap.

The compression spring 90 that bears against the undersurface of the disc portion 84 of the actuator 83 tends to force the disc flat against the undersurface 100 of the push button 25. However, the lower end of the inwardly inclined section 96 of the actuating arm, by engaging the edge 98 of the slot 92, prevents the disc 84 from assuming such a position. Instead, only a corner 101 of the disc 84, where the first section 95 of the arm 85 is connected, can be brought into contact with the undersurface 100 of the push button 25 by the force of the spring 90.

The insert 33 that fits over the upper end of the oval reservoir section 32 of the cartridge 28 has a V-shaped upper wall defined by a surface 102 adjacent the periphery of the cap and a surface 103 on the inner side adjacent the surface 47 of the carrier 27. The outer surface 102 slopes downwardly away from the axis of the pen, while the inner surface 103 is inclined downwardly toward the

axis. Adjacent the inside top surface 103 is a second tab 104, which is thereby located on the opposite side from the outer tab 75.

In a similar manner, the end element 38 of the cartridge 29 has a V-shaped upper end wall defined by an outer surface 105 and an inner surface 106 adjacent which is a tab 107.

When the device is in the position of FIGURE 2, the ink cartridge 28 is extended by pushing downwardly on the button 25 at the upper end of the cap 23, causing the parts to assume the relationship of FIGURE 3. When this is done, the undersurface 100 of the push button pushes downwardly on the corner 101 of the actuating member 83, so that the member 83 moves downwardly as the arm 85 becomes extended further through the slot 93. As this occurs, the arm 85 is guided by the engagement of the inwardly inclined section 96 of the arm with the edge 98 of the slot 92. Consequently, despite the offcenter reaction against the disc 84, the latter portion 20 of the actuator 83 still cannot assume a position of flat engagement with the undersurface 100 of the push button 25. Therefore, as the push button 25 commences its stroke, the lower end 99 of the arm 85 moves inwardly only very slightly and, as the downward movement continues, comes into engagement with the outer inclined surface 102 to force the ink carriage 28 downwardly with it. The outer tab 75 at the upper end of the cartridge 28 moves through the longitudinal slot of the split sleeve 62 as the cartridge is shifted downwardly by the actuating arm. The slot 65 and tab 75 guide the upper end of the cartridge in a straight path longitudinally of the pen. This downward travel of the cartridge 28 will extend the lower cylindrical portion 30 with its ball point 31 through the opening 78 in the tip 77 of the barrel.

With reference to FIGURE 12, the reaction of the actuating arm 85 against the inclined surface 102 generates a lateral force component F_1 in addition to the vertical force component F_2 that moves the cartridge 28 downwardly. The lateral force component F_1 , therefore, will tend to move the upper end of the cartridge 28 toward the axis of the pen, so that the tab 104 is brought into contact with the flat surface 47 of the carrier 27. Thus, as the cartridge moves downwardly, the tab 104 slides along the flat surface 47. This movement continues until the recess 49 is reached. At that point, the side reacting force causes the upper end of the cartridge 28 to be tilted inwardly and the tab 104 to enter the recess 49. When this occurs, the tab 104 is locked in the recess 49. The tab 104 and the wall of the opening 49 act as abutments that hold the ink cartridge 28 in its extended position with the ball end 31 projected beyond the end of the tip 77 of the barrel.

Thereafter, when the push button 25 is released, the compression spring 90 returns it to its elevated position, and the actuator 83 likewise assumes its original position. The ink cartridge 28, however, stays in its extended position, held in place by the tab 104 that is trapped in the recess 49 in the surface 47 of the carrier 27. In this position, of course, the pen is used for writing.

The cartridge 28 is retracted into the body of the pen simply by another downward stroke of the push button 25. If again the push button 25 is pressed, the actuator 83 will move through the slot as before as the inwardly inclined section 96 guides this element along the inner edge 98 of the slot 92. However, the cartridge no longer is in the way of the lower end 99 of the actuating arm, so that it does not encounter the surface 102 upon the initial movement of the actuator 83. Instead, however, the intermediate actuating arm section 96 will ride along the edge 98 of the slot as the arm moves further downwardly. Because the section 96 inclines outwardly from its lower end to its upper end, this greater unrestricted downward movement of the arm 85 will allow the bottom end 99 of the arm to move toward the carrier surface 47. As the spring 90 tends to flatten the disc part 84 of the

actuator 83 against the undersurface 160 of the push button, the actuator will be allowed to pivot about the corner 101 to bring the bottom end 99 inwardly toward the pen axis.

In order to permit a full inward arc of movement for the lower end of the actuator, the distance between the axis of the disc part 84 and the portion of the arm 85 adjacent the slot edge 98 when the arm is at the end of its downward stroke should be greater than the spacing between the axis and the edge surface 98. If this spacing is not maintained, there will be an interference at the inner edge 98 of the slot 92 that will prevent the actuator from pivoting through a maximum arc to bring the bottom end 99 inwardly to the surface 47.

As the actuator 83 moves downwardly, this simultaneous pivotal movement of it enables the lower end 99 of the arm 85 to contact the surface 103, rather than the surface 102, of the upper end 33 of the ink cartridge 28. As a result, because of the inclination of the surface 103, the end 99 then produces a reaction F_3 on the upper end of the ink cartridge tending to move it laterally away from the axis of the pen (see FIGURE 13). Consequently, the upper end of the cartridge is tilted away from the carrier 27 and the tab 104 is brought out of the recess 49. Hence the tab 104 no longer acts as a stop to retain the cartridge 28 in its extended position.

When the push button 25 is released after this occurrence, it is returned to its normal elevated position by the spring 90. Also, the compression spring 59 at the lower end of the cartridge 28 forces the cartridge 28 back upwardly to where the outer tab 75 enters the annular groove 72 and the ball point 31 of the pen is withdrawn into the tip 77 of the barrel. The slot 65 cooperates with the tab 75 to guide the cartridge during this upward movement.

Of course, when the cartridges 28 and 29 are reversed, a similar action takes place, with the surface 105 engaging the end 99 of the actuator to lock the cartridge in its extended position, while the other end surface 106 is utilized in kicking the tab 107 from the recess 49 in allowing the cartridge to be retracted.

As a result of this mechanism, therefore, a single push button is utilized both to extend and to retract the cartridge of the pen. There are no awkward side controls on the pen, with the extension and retraction both being accomplished by the familiar and easily manipulated push button action. The upper spring 90 maintains the push button in an elevated position whenever it is released, including when the ink cartridge is extended, so that there is never a loose part at the push button as occurs in many pen constructions. Not only does the single push button accomplish extension and retraction of the cartridge, but also it is used in actuating either of two selectively positioned cartridges. The user of the pen need turn only the collar 22 in selecting the cartridge to be used for writing and then utilize the same mechanism in an unvaried way in effecting the extension and retraction. In addition to this convenience of use, the parts are designed so that there is very little wear, and long periods of satisfactory service are realized. Furthermore, the elements are of low cost construction and adapted for mass production techniques.

One of the advantages of the arrangement of this invention is its compactness and the fact that it permits the pen to be made with a slim barrel, yet to utilize cartridges having a full supply of ink. The extension and retraction elements are located at the upper end of the cap of the pen and occupy only a small part of the total axial length of the pen. The indexing arrangement that includes the groove 72 and the collar 22 that cooperates with the tab 81 of the carrier 27 virtually occupies no space that detracts from the supply of ink.

A further advantage lies in the use of the carrier 27 and the oval-shaped reservoir sections 32 and 37 of the ink cartridges 28 and 29. Each cartridge, by virtue of the

contour given to it, occupies a major portion of the cross section of the half of the barrel in which it is located. A conventional round ink cartridge displaced to one side of the axis of the pen necessarily occupies considerably less volume of the barrel cross section than the oval reservoirs of the present invention. This greater volume of the cartridges 28 and 29 is used to retain ink so that the cartridges hold far more than any other selective cartridge pen that does not necessitate an exceedingly large diameter barrel.

The oval shape of the cartridge reservoir lends itself to volume production of these items. This permits the cartridge reservoirs initially to be round tubes, filled with ink and then flattened. Alternatively, the reservoir may be made semicircular in cross section, which will allow a slightly greater ink capacity. However, this adds to the cost of manufacture, because the semicircular shape necessitates contouring the reservoir about a mandrel inserted into it, and the filling operation must take place afterwards. No mandrel is needed when the reservoir is flattened from a circular to an oval shape.

In the arrangement described above, the cartridge is bodily tilted slightly as the cartridge is extended and retracted. The pen may be constructed so that the cartridge itself need not be tilted, with only the upper end insert of the cartridge making such movement. This assures that the outer tab will never leave the groove 65, so that there is no possibility of the parts jamming due to misalignment of the tab following ejection of the retainer tab from the recess in the carrier. Such a construction is shown in FIGURE 14.

Here, the upper end member 108 again may be made of plastic, with its bottom part inserted into the upper end of the reservoir of the ink cartridge 109. Adjacent the inner wall of the cap 23 is a tab 110 receivable in the vertical slot 65, serving a function similar to that of the tabs 75 and 76 described above. A substantially V-shaped recess 111 is formed in the end of the element 108, from which projects a web 112 of lesser thickness than the width of the recess 111. The device is constructed so that flexure is possible at the relatively narrow base of the web 112, which is integral with the remainder of the end element 108. Beyond the web 112 is a block 113 having a V-shaped end defined by an outer surface 114 and an inner surface 115. These latter two surfaces correspond, of course, to the surfaces 102 and 103 of the cartridge 28 described above. A tab 116 projects from the inner wall of the member 113 adjacent the inner end surface 115.

Consequently, in use of the arrangement of FIGURE 14, the actuating arm 85 moves downwardly initially to cause engagement of the lower end 99 with the surface 114 adjacent the circumference of the cap 23. The sideways component of the force on the surface 114 causes the block 113 to move inwardly so that the tab 116 is brought against the surface 47 of the carrier 27 as the web 112 flexes about its base where it joins the lower portion of the end member 108. This bending movement is permitted by the clearance between the web and the wall of the slot 111. With the tab 116 forced inwardly against the carrier surface 47 as the cartridge moves downwardly, it will be caused to enter the recess 49 when sufficient travel of the cartridge has taken place. The tab 116 in this manner is trapped in the recess 49, and the cartridge is held in the extended position for writing.

In retracting the cartridge, the actuating member 83 again is moved downwardly, with the end 99 then engaging the inner surface 115 of the block 113 because of the greater amount of inward pivoting permitted the member 85. Consequently, the side reaction force kicks the tab 116 out of the recess 49, and the cartridge is released. Then, as before, the compression spring at the base of the cartridge 109 will retract it to its raised position. During the extension and retraction of the ink cartridge, it moves only axially as all the lateral motion is made by

the end part 113. The tab 110 is guided at all times in the longitudinal slot 65.

Another arrangement for locking and unlocking the cartridge in its extended position through a pivotal element at the upper end of the ink cartridge, rather than by tilting the entire cartridge bodily, is illustrated in FIGURE 15. Here, the rotation of the end element is made possible through a hinged construction, instead of by the flexure of the material itself. As seen in FIGURE 15, the ink cartridge 117 includes a plastic end insert 118 provided with a V-shaped recess 119 at its upper end. The bottom of the V-shaped recess 119 communicates with a lower opening 120 of circular shape. A separate pivotal element 121 includes a depending beam 122 extending into the recess 119. At the bottom of the beam 122 is an enlarged portion 123 defined by a segment of a cylinder. The latter part fits within the lower opening 120 in the end of the member 118. Consequently, through the clearance provided between the beam 122 and the wall of the recess 119, the member 121 is free to pivot between an outer position adjacent the wall of the cap of the pen, and an inner position next to the carrier surface 47.

On the upper end of the member 121 are inclined converging surfaces 124 and 125 on the outer and inner sides of this member, respectively. These surfaces correspond to the surfaces 114 and 115 of the element 113 in the previously described embodiment. Thus, as before, when the bottom end 99 of the actuating arm 85 initially moves downwardly to extend the ink cartridge, it will contact the outer inclined surface 124, producing an inward component as well as the component axially of the cartridge. Upon movement of the actuating arm through the downward stroke, the lateral force component will cause the member 121 to rotate inwardly so that the tab 126 on the inner side of the pivotal member 121 will enter the recess 49 in the carrier 27. This locks the cartridge 117 in its extended position.

Release of the cartridge is accomplished by another downward stroke of the push button, whereupon the end 99 of the actuating arm 85 contacts the inner inclined surface 125 of the member 121. This results in a lateral force component away from the axis of the pen, pivoting the member 121 outwardly so that the tab 126 is free from the restraint of the recess 49. This allows the cartridge 117 to be moved to its retracted position by the compression spring at the lower end.

With the pivotal movement occurring only at the element 121, the tab 127 on the outer side of the end member 118 will always remain in the vertical slot 65 in the split sleeve 62. Thus, with no tilting of the cartridge necessary, it is assured that the cartridge is positively guided in all phases of its movement.

In the arrangement of FIGURES 16 and 17, there is no tilting of either the cartridge or a member carried by it, and instead the cartridge is held in an extended position by a deflectable tab located on the central wall of the carrier for the cartridges. In this construction, the carrier 128 has a wall 129 corresponding to the upper portion of the carrier 27 previously described. Located on the carrier wall 129 at a position generally corresponding to that of the recess 49 of the embodiment described above is a pair of tabs 130 and 131, integral with the wall 129 at their upper edges. In their free positions, the tabs 130 and 131 extend laterally away from the wall in opposite directions.

Located on one side of the wall 129 is an ink cartridge 132. The upper end insert 133 of the cartridge 132 has a tab 134 of the usual type adapted to fit in the vertical slot 65 of the split sleeve 62 as well as entering the groove 72 at the time the cartridges are indexed. The element 133 is formed with a V-shaped end, having an outer surface 135 and an inner surface 136. A short straight section 137, radial with respect to the ink cartridge, con-

ncts to the lower edge of the inner inclined end surface 136.

On the opposite side of the wall 129 of the carrier 128 is a second ink cartridge 138, similar to the cartridge 132. As before, the cartridges are indexed through rotation of the carrier 128 to locate one of the cartridges beneath the actuating arm 85.

In operation of this unit, the downward force from the actuating arm is first transmitted through the outer surface 135 to move the cartridge 132 downwardly to its extended position. There is no tilting movement of the cartridge, nor pivotal movement of the top end part 133 as the cartridge is shifted downwardly. The movement takes place until the lower edge of the tab 130 is reached, at which time the tab springs outwardly to fit over the surface 137 at the inner end of the cartridge. Prior to this time, the tab 130 will be retracted into the wall 129 because the cartridge 132 will prevent it from assuming its free position. After the tab 130 has been permitted to move outwardly over the surface 137, upon release of the push button, the tab 130 holds the cartridge 132 in the extended position, as shown in FIGURE 16.

In order to return the cartridge to its retracted position, the push button is again actuated and, as before, the lower end 99 of the actuating arm can move inwardly further because it will not immediately contact the upper end of the cartridge as the downward movement of the arm takes place. Consequently, the end 99 of the actuating arm will strike the tab 130 as it moves downwardly. This produces a force biasing the tab 130 inwardly to retract it within the confines of the carrier wall 129. Thus, the arm 85 forces the tab inwardly to where it moves off the end edge surface 137, freeing the cartridge 132. This allows the cartridge 132 to move upwardly to its retracted position. As this occurs, the tab 130 is held flush with the wall 129 of the carrier by the side of the cartridge 132. Later, it will spring outwardly again when the cartridge again is extended to its writing position.

Naturally, a similar action takes place for the other cartridge 138 when it is indexed beneath the actuating arm 85, with the tab 131 being used to retain it in the extended position.

The extension and retraction mechanism is readily adapted to single-cartridge pen construction, as shown in FIGURES 18 and 19. In such instances, the pen may be made to have an oversize ink cartridge providing an exceptionally large reservoir of available ink. The cartridge 140 may be circular in cross section to occupy the major portion of the volume within the cap and barrel of the pen because only one cartridge is present. The cartridge 140 is slightly smaller in diameter than the inside wall of the cap 141 so that the cartridge is capable of tilting with respect to the axis of the pen. The end insert 142 for the top end of the cartridge 140 has an upper wall defined by two intersecting conical surfaces. The inner portion 143 is a full conical section having its apex facing upwardly. The base of the conical surface 143 meets the bottom edge of a frustoconical outer surface 144 that extends upwardly and outwardly to the circumference of the element 142.

Received in the upper portion of the cap 141 is a member 146 having a lower cylindrical portion 147 that engages the inner wall of the cap with a press fit. The section 147 includes an elongated extension 148 on one side and a short extension 149 on the other. A radial end wall 150 extends across the upper end of the cylindrical portion 147, and a post 151 projects axially from this surface. The cut-away portion for the actuating arm is on the side of the short extension 149 of the cylindrical portion 147, and is defined by slots 152 and 153 in the walls 147 and 150, respectively.

The actuator 154 is generally similar to the actuator 83, including a disc portion 155 received on the post 151 above a compression spring 156. The actuating arm 157 extends from one side of the disc portion 155, providing

a corner 158 that bears against the undersurface 159 of the push button 160. The arm 157 includes an upper portion 161 that extends from the disc part 155 at slightly less than 90°. Beneath the arm section 161 is the intermediate portion 162 that inclines inwardly toward the axis of the pen, and joins the lower portion 163 that terminates in a doubled-over end 164.

In the elevated position of FIGURE 18, the lower part of the arm section 162 is at the slot 153, so that the actuating arm bears against the inner edge 165 of the slot 153. This holds the actuating arm outwardly with respect to the axis of the pen, so that the compression spring 156 cannot force the disc section 155 into flat engagement with the undersurface 159 of the push button 160.

When the push button 160 is pushed downwardly, the reaction against the corner 158 of the actuator forces the actuating arm 157 also downwardly through the slot 153. As this movement commences, the lower end 164 of the actuating arm 157 engages the upwardly directed conical surface 143 of the end piece 142 of the ink cartridge 140. This engagement is on the side of the pen axis opposite from the extension 148 of the cylindrical part 147 of the member 146. Because of the inclined nature of the conical surface 143, there is a lateral component of force urging the upper end of the pen cartridge to the right as the device is illustrated in FIGURE 18, causing the outer edge of the top piece 142 to engage and slide along the inner wall of the bottom extension 148 of the cylindrical section 147. This movement continues until the lower edge 166 of the extension 148 is reached, at which time the top of the cartridge is free to move further to the right to cause the upper edge of the cartridge to engage the inner wall of the cap 141. This positions the upwardly inclined surface 144 of the end piece 142 beneath the bottom edge 166 of the extension 148. Therefore, upon release of the push button and the raising of the actuating arm 157, the surface 144 will engage the lower edge 166, thereby holding the cartridge in its lower or extended position. In this manner, the surfaces 144 and 166 of the cartridge assembly and retainer sleeve 146 provide an abutment and a recess to hold the cartridge as in the mechanisms described above. Preferably, the edge 166 is undercut as illustrated to facilitate its retention of the cartridge at the surface 144.

In order to release the cartridge, the push button again is actuated, bringing the arm downwardly through the slot 153 and causing the intermediate section 162 to slide along the inner edge 165 of the slot. Because the ink cartridge is not met by the initial movement of the actuating arm, it is permitted to pivot about the corner 158, so that the lower end 164 of the arm moves inwardly and past the axis of the pen toward the lower end extension 148 of the member 146. This means that the bottom end 164 of the actuating arm will cross the apex of the surface 143 to engage the surface 143 on the opposite side of the apex. Thus, the actuating arm engages differently inclined surface portions in the extension and retraction strokes. When the engagement is past the apex, there is a lateral component of force generated, tending to move the upper end of the pen cartridge back to the left as the device is illustrated. Therefore, in the retracting stroke of the push button, the actuating arm pushes down on the surface 143 and removes the surface 144 from beneath the edge 166 of the extension 148 of the member 146. This tilts the upper end of the cartridge 140 back toward the left of the device, as shown in FIGURE 18, so that, upon release of the push button, the spring on the ink cartridge returns the cartridge to its elevated position. In the raised position, the opposite edge of the upper end of the top piece 142 of the cartridge 140 contacts the bottom edge 167 of the short extension 149 beneath the slot 152, which thereby stops the cartridge at its elevated position.

It should be noted that, when a single cartridge is utilized, it is not required that provision be made for aligning the cartridge rotationally with the actuating arm

to assure that the upper end of the cartridge will be held in its extended position. Before, it was necessary to assure that the horizontal axes of the inclined surfaces at the upper end of the ink cartridge were substantially parallel to the surface 47 of the carrier in which was formed the recess 49. This was in order that the inner locking tab would always be forced into the recess 49 as the cartridge was moved downwardly. With the single-cartridge construction, however, symmetrical conical surfaces can be utilized at the top end of the cartridge, and will lock under the bottom edge 166 of the extension 148, regardless of the rotational position of the cartridge. The mechanism becomes even simpler for the single-cartridge arrangement than it is for the dual-cartridge construction. It should be noted also that, if desired, a pivotal element could be provided at the upper end of the cartridge 140 for the single-cartridge construction instead of employing a tilting cartridge as in the design illustrated.

If desired, the actuating arm and push button may be made integral to further simplify the construction and assembly of the pen. This arrangement is shown in FIGURE 20. Here, the push button 169 is apertured to receive the post 170 of the top insert 171, the latter element corresponding to either the part 69 or 146 described above. In this embodiment, a modified spring installation is shown, with the compression spring 172 being located within the axial opening 173 in the push button immediately above the post 170. This spring position is possible because it only provides an axial force on the push button and does not react on the actuating arm.

From one side of the lower surface 174 of the push button extends an actuating arm 175 that fits through the slot 176 in the member 171. The arm 175 is made as a spring that is biased inwardly against the inner edge 177 of the slot 176. It is an inclined element, held outwardly by the edge 177 when the push button 169 is held in the raised position by the spring 172. This means that the bottom end 178 of the actuating arm 175 will engage the outer surface of the upper end of the ink cartridge upon depression of the push button 169. For release of the cartridge, upon extending the push button downwardly, the arm 175 rides along the edge 177 and, by virtue of the inward bias inherent in the construction of the arm 175, its bottom end 178 will then move inwardly. This allows it to engage the opposite inclined surface of the ink cartridge to release it from its retaining element.

The foregoing detailed description is to be clearly understood as given by way of illustration and example only, the spirit and scope of this invention being limited solely by the appended claims.

I claim:

1. A project-retract mechanism for a pen having an elongated tubular housing having a cap end and a tip end, an ink cartridge means in said housing, said cartridge means having an ink dispensing end and being movable axially between a retracted position in which said end is withdrawn into said housing and an extended position in which said end projects from said tip end of said housing, comprising

surface means on the opposite end of said cartridge means, said surface means being convergent axially outwardly with respect to said cartridge means to an apical portion laterally inward of the wall of said housing,

an actuating means for moving said cartridge means to said extended position,

said actuating means including an arm movable longitudinally of said housing

from a first outer position

to a second inner position,

said arm having an end engageable with said surface means at said opposite end of said cartridge means,

said arm including resilient means biasing said end

13

of said arm toward one side of said apical portion,
guide means for preventing said arm from moving to said one side of said apical portion until said arm has been positioned longitudinally relatively adjacent 5 said second inner position,

whereby when said cartridge means is in said retracted position advancement of said arm inwardly from said first outer position will cause said end of said arm to engage said surface 10 means of said cartridge means on the opposite side of said apical portion,

and when said cartridge means is in said extended position advancement of said actuating arm inwardly from said first outer 15 position will cause said end of said actuating arm to exert a lateral force component on said one side of said apical portion,

said convergent surface means of said cartridge means being inclined with respect to the axis of 20 said cartridge means so as to cause said actuating arm to exert a lateral force component on said opposite end of said cartridge means upon such engagement therewith biasing said opposite end of said cartridge means laterally toward the 25 side of said housing opposite from the side of said apical portion engaged by said end of said arm,

and an abutment in said housing on said one side of 30 said apical portion,

said cartridge means including a cooperative abutment engageable with said first-mentioned abutment upon movement of said cartridge means to said extended position and in response to the lateral force component exerted by said actuating 35 arm,

the lateral force component upon engagement by said actuating arm with said surface means of said cartridge means on said one side of said apical portion when said cartridge means is in said extended position moving said abutments out of interengagement,

whereby said cartridge means is movable to said retracted position.

2. A device as recited in claim 1 in which two of said cartridge means are included in said housing substantially in parallelism, 45 and including in addition a carrier for retaining said cartridge means,

said carrier having a wall intermediate said cartridge means, 50 means independent of said actuating means for rotating said carrier substantially about the longitudinal axis of said housing

for selectively bringing each of said cartridge means in a position of adjacency with said end 55 of said actuating arm while the cartridge means not so brought into adjacency is located remote from said end of said actuating arm.

3. A device as recited in claim 2 in which said tip end of said housing converges to a location 60 offset from the axis of said housing toward one side thereof,

said opening being in said location, 65 and including means for extending one of said cartridge means into said tip end partially toward said projected position when said one cartridge means is brought into said position of adjacency with said end of said actuating arm,

and simultaneously withdrawing the ink dispensing end of the other of said cartridge means 70 from said tip end while positioning the opposite end of said other cartridge means laterally to one side of said actuating arm and relatively closer to said cap end than is said end of said actuating arm.

14

4. A device as recited in claim 1, in which said opposite end of said cartridge means includes an end member,

said end member having a base portion attached to said cartridge means, and a beam portion,

said beam portion being bendable to allow pivotal movement thereof relative to said cartridge means,

said beam portion including said convergent surface means and said abutment of said cartridge means so that said beam portion is bendable by said actuating arm for moving said abutment of said cartridge means laterally in one direction relative to the remaining portions of said cartridge means to bring said abutment of said cartridge means into engagement with said first mentioned abutment and bendable in the opposite direction by said actuating arm for disengaging said abutments from each other.

5. A device as recited in claim 1 in which said opposite end of said cartridge means includes an end member,

said end member having a first portion connected to said cartridge means, a second portion,

and a hinge connecting said first portion to said second portion of said end member for pivotal movement about an axis transverse to the axis of said cartridge means,

said second portion defining said convergent surface means and including said abutment of said cartridge means, said second portion of said end member being pivotal about said hinge in response to said lateral force component of said actuating member.

6. A project-retract mechanism for a pen having a housing having a tip end portion, ink cartridge means in said housing movable relative thereto between a retracted position and a projected position in which an end of said ink cartridge projects from said tip end of said housing, and spring means biasing said cartridge means toward said retracted position, comprising

an actuating member movable through a stroke toward and away from said tip end and engageable with a section of said cartridge means when so moved toward said tip,

said section including a plurality of oblique surface portions,

guide means for causing said actuating member to assume a first lateral position to engage one of said oblique surface portions when said actuating member is moved toward said tip and said cartridge means is in said retracted position to exert a force on said cartridge means to move said cartridge means longitudinally to said projected position and to move said section of said cartridge means laterally in one direction, and retainer means in said housing engageable with said cartridge means when said cartridge means is so moved longitudinally and laterally for holding said cartridge means in said projected position,

said guide means including means for causing said actuating member to move laterally in said one direction beyond said first position when said actuating member is moved toward said tip when said cartridge means is in said projected position for causing said actuating member to engage a different oblique surface portion for exerting a lateral force in a different direction on said cartridge means and moving said cartridge means out of engagement with said re-

15

tainer means for permitting movement of said cartridge means to said retracted position.

7. A device as recited in claim 6 in which two of said cartridge means are received in said housing, and including means independent of said cartridge-positioning means for selectively moving said cartridge means into operative relationship with said actuating member, and in which at least a portion of said housing is cylindrical, each of said cartridge means including an ink-retaining reservoir portion in said cylindrical portion of said housing, 5 said reservoir portions being on opposite sides of a diameter of said cylindrical portion, each reservoir portion being noncircular in cross section 15 enlarged in the direction of said diameter for thereby providing an increased ink capacity.
8. A device as recited in claim 6 in which two of said cartridge means are received in said housing, 20 and including means for indexing said cartridge means, said indexing means including a carrier to hold said cartridge means substantially in parallelism, and means independent of said cartridge-positioning means for rotating said carrier substantially about the axis of said housing to selectively position said cartridge means in operative relationship with said actuating member for operation thereby, said tip end portion being convergent to a location offset of the longitudinal axis of said housing, said indexing means including means to longitudinally extend one of said cartridge means into said tip end portion when said one cartridge means is in operative relationship with said actuating member, 25 and simultaneously to longitudinally withdraw the other cartridge means from said tip end portion. 30

9. A project-retract mechanism for a pen having a housing, an ink cartridge means in said housing, said cartridge means having an ink dispensing end and being movable relative to said housing between a retracted position in which said ink dispensing end is in said housing and an extended position in which said end is projected from said housing, and resilient means biasing said cartridge means to said retracted position, said mechanism comprising 40 inclined surface means on said cartridge means at the opposite end thereof,

said surface means providing a first surface means inclining longitudinally inwardly and laterally 50 outwardly toward one side of said housing, and a second surface means inclining longitudinally inwardly and laterally outwardly toward the opposite side of said housing,

and actuating means for imparting said movement to 55 said cartridge means,

said actuating means including an arm having an end adjacent and beyond said opposite end of said cartridge means,

said arm being movable inwardly with respect to said cartridge means for engaging said opposite end and moving said cartridge means therewith,

guide means positioning said end of said arm adjacent said first surface means of said cartridge 65 means when said cartridge means is in said retracted position with respect to said housing,

whereby upon said inward movement said end engages said first surface means and produces thereon

a longitudinal reaction force for moving said cartridge means longitudinally of said housing for extending said ink-dispensing end through said opening, and a lateral reaction force urging said 75

16

opposite end of said cartridge means toward said opposite side of said housing,

said housing and said cartridge means including interengageable abutment means for retaining said cartridge means upon a predetermined amount of said longitudinal and lateral movement of said cartridge in response to such movement of said arm,

said guide means causing said end of said arm to move laterally toward said opposite side of said housing upon a subsequent inward stroke of said arm for causing said end of said arm to engage said second surface means

for producing a lateral reaction force urging said opposite end of said cartridge means toward said one side of said housing and causing disengagement of said abutment means and the release of said cartridge means therefrom.

10. A device as recited in claim 9 in which at least a portion of said housing is cylindrical, said arm of said actuating means is adjacent said one side of said housing, two of said cartridge means are included in said housing substantially in parallelism, and including in addition a carrier for retaining said cartridge means,

said carrier having a wall intermediate said cartridge means, said carrier being rotatable substantially about the longitudinal axis of said housing

for selectively bringing each of said cartridge means to said one side of said housing in a position of adjacency with said end of said actuating arm,

each of said cartridge means having a reservoir portion in said cylindrical portion that is noncircular in cross section, being enlarged in one direction to a width approaching the diameter of the section of the housing within which the cartridge means is located and extending in the other direction a distance approaching the length of the radius of the housing section within which it is located.

11. A device as recited in claim 10 including in addition

an oblique guide passage in said housing, each of said cartridge means having an element extending into said guide passage, said guide passage having an axially inner portion on said one side of said housing adjacent said end of said actuating arm, and an axially outer portion on said opposite side of said housing adjacent said end of said actuating arm,

whereby the cartridge means positioned by said carrier adjacent said end of said actuating arm is moved axially by said guide passage toward said opening in said housing, while the other of said cartridge means is moved by said guide passage axially away from said opening in said housing and to a position laterally to one side of said end of said actuating arm.

12. A project-retract mechanism for a pen having an elongated tubular housing having a tip end and a cap end, an ink cartridge in said housing, said ink cartridge having an ink dispensing end, and being movable axially relative to said housing between a retracted position in which said ink dispensing end is in said housing and an extended position in which said ink dispensing end is

extended through said tip end of said housing, and resilient means biasing said cartridge to said retracted position, said mechanism comprising

5

actuating means for effecting said movement of said cartridge,

10

said actuating means being movable axially with respect to said housing

15

from a first position axially outwardly of the opposite end of said ink cartridge to a second position for engaging said opposite end and moving said ink cartridge therewith axially of said housing from said retracted to said extended position,

20

said opposite end of said cartridge including surface means converging axially outwardly with respect to said cartridge and toward an apical portion laterally inwardly of the inner surface of said housing,

25

and guide means for causing and actuating means to engage said surface means on one side of said apical portion adjacent one side of said housing upon said movement of said actuating means when said ink cartridge is in said retracted position,

30

whereby said actuating means produces a lateral force component biasing said opposite end of said cartridge away from said one side of said housing,

35

and abutment means in said housing remote from said one side thereof,

40

said cartridge including an abutment means engageable with said first-mentioned abutment means upon a predetermined axial movement of said cartridge in response to the force exerted by said actuating means,

45

said lateral force component urging said abutment means into interengagement,

50

said guide means including means for causing lateral movement of said actuating means so that said actuating means engages said surface means on the opposite side of said apical portion upon advancement of said actuating means toward said cartridge when said cartridge is in said extended position

55

for causing said actuating means to exert a lateral force component biasing said opposite end of said cartridge toward said one side of said housing

60

for thereby disengaging said abutment means for permitting said resilient means to move said cartridge to said retracted position.

13. A device as recited in claim 12 in which said actuating means includes

65

a push button at one end of said housing, said push button being movable axially inwardly with respect to said housing toward said opposite end of said cartridge,

70

an actuating member,

75

said actuating member having a first portion adjacent said push button,

and a second portion extending angularly from said first portion toward said opposite end of said cartridge,

80

said actuating member being in engagement with said push button at a location intermediate said first and second portions of said actuating member, resilient means urging said first portion of said actuating member toward a position of engagement with said push button,

85

for causing pivotal movement of said actuating member about said intermediate location,

said guide means including

90

a guide surface in said housing adjacent said second portion of said actuating member and normally in engagement therewith for limiting the amount of such pivotal movement of said actuating member,

95

said second portion of said actuating member so engaging said guide surface being inclined inwardly with respect to the axis of said housing from an outer portion remote from said opposite end of said cartridge to an inner portion adjacent said opposite end of said cartridge,

100

to permit increasingly greater amounts of said pivotal movement as said actuating member is moved axially inwardly of said housing by axially inward movement of said push button,

105

the axially inner end of said second portion of said actuating member being movable upon said pivotal movement of said actuating member

110

from a first lateral position adjacent said one side of said housing

115

to a second lateral position relatively more remote from said first side of said housing,

120

whereby said end of said actuating member can engage said surface means on said one side of said apical portion when said cartridge is in said retracted position and said surface means on said opposite side of said apical portion when said cartridge is in said extended position.

14. A pen comprising

125

an elongated tubular housing,

130

a duality of ink cartridge means in said housing, each of said ink cartridge means having an ink-dispensing end,

135

and an oblique surface portion remote from said ink-dispensing end,

140

said housing having an aperture therethrough, each of said cartridge means being movable longitudinally of said housing between

145

an extended position in which said ink-dispensing end projects through said aperture and a retracted position in which said ink-dispensing end is withdrawn into said housing,

150

and cartridge-positioning means for selectively positioning said cartridge means in either of said positions,

155

said cartridge-positioning means including an actuating member,

160

a carrier means for holding said cartridge means substantially in parallelism with said housing and guiding said cartridge means for longitudinal rectilinear movement from said retracted position to said extended position,

165

said carrier means being movable to bring said cartridge means selectively into operative relationship with said actuating member,

170

said actuating member being movable through a stroke from a first to a second position, guide means for causing said actuating member to engage said oblique surface portion of the one of said cartridge means in said operative relationship with said actuating member for exerting a force on said one cartridge means for moving said one cartridge means from said retracted to said extended position upon said movement of said actuating member through said stroke when said one cartridge means is in said retracted position,

19

and retainer means in said housing engageable with said one cartridge means when said one cartridge means is so moved to said extended position

for thereby holding said one cartridge means 5 in said extended position,

said guide means including means for causing said actuating member to move laterally to disengage said one cartridge means and said retainer means upon subsequent movement of said actuating member through said stroke 10

for releasing said one cartridge means for permitting movement of said one cartridge means to said retracted position.

15. A device as recited in claim 14 in which said carrier means includes a wall interposed between said cartridge means,

said retainer means including a spring tab carried by said wall for each of said cartridge means, each of said tabs normally being held retracted 20 relative to said wall by the side of the cartridge means therefor,

each tab being released for movement outwardly when said cartridge means has been moved to said extended position,

each of said cartridge means having a surface engageable by the end of the tab therefor when said tab is released for holding said cartridge means in said extended position,

said guide means including means for causing 30 said actuating member to engage the tab of a cartridge held in said extended position upon movement of said actuating member through its stroke,

for deflecting said tab to said retracted position and releasing the cartridge means held thereby.

35. A project-retract mechanism for a pen having a housing having a tip end, an ink cartridge means movable relative to said housing between a retracted position and a projected position in which said ink cartridge means projects through said tip end, and spring means biasing said cartridge means toward said retracted position, comprising

cartridge positioning means for positioning said cartridge means in either of said positions,

20

said cartridge positioning means including an element movable longitudinally of said housing toward and away from said tip end, said cartridge positioning means including means for biasing said element laterally relative to said housing during said longitudinal movement of said element, and

guide means for controlling the amount of lateral movement of said element to result in greater lateral movement within increased longitudinal movement toward said tip end,

said element being engageable with one surface of said cartridge means upon movement of said element when said cartridge means is in said retracted position for moving said cartridge means therewith to said projected position, and exerting a lateral force on said cartridge means for effecting lateral movement of said cartridge means at said one surface,

said cartridge positioning means including a detent means engageable by said cartridge means upon said movement of said cartridge means longitudinally and laterally,

said element being moveable laterally a greater amount to disengage said cartridge means from said detent means when said element is moved toward said tip end when said cartridge means is in said projected position.
